JACK

Filed May 2, 1927

UNITED STATES PATENT OFFICE

ELMER E. SARR, OF HURON, OHIO, ASSIGNOR OF ONE-HALF TO HIRAM C. WEITZMAN,
OF HURON, OHIO

JACK

Application filed May 2, 1927. Serial No. 188,347.

The present invention relates to improvements in jacks, and the primary object of the invention is to provide an improved type of jack primarily intended for use in connection with the legs of furniture such as tables of various characters, chairs, and the like, for use as a leveling means therefor.

A further object of the invention is to provide a jack of the character set forth embodying an elevating means for causing the lift to travel in a perfectly parallel relation with respect to its base or supporting section.

A further object of the invention is to provide an improved type of jack as set forth embodying substantially flat base and lift sections with wedge acting elevating means disposed between the sections and operable for forcibly moving the sections in opposed directions with a minimum amount of friction.

A still further object of the invention resides in the provision of an improved type of jack as set forth embodying relatively few and simple parts, and which jack is of such construction as to permit of the device being formed relatively shallow as to its over-all height.

A still further object of the invention is to provide an improved type of jack for use in connection with table legs and the like, embodying novel features of assembly and features of construction whereby the interior of the device is rendered practically dust and moisture proof.

Other objects and advantages of the invention will be apparent during the course of the following detailed description, take in connection with the accompanying drawing forming a part of this specification and in which drawing:

Figure 1 is a central vertical section through the improved jack taken longitudinally of the power screw and showing an element such as a table leg or the like supported by the jack.

Figure 2 is a central vertical section through the jack on the line 2—2 of Figure 1 and looking in the direction of the arrows.

Figure 3 is a top plan view of the base section of the jack and showing the arrangement

of the lift or elevating means for movement of the cap section away from the base section.

Figure 4 is a perspective view of the inner side of the cap or lift section and showing portions of the side walls broken away for better illustrating the specific construction of the cap section.

Figure 5 is a perspective view of one of the wedge members of the elevating means.

Figure 6 is an enlarged fragmentary detail view of the power screw.

Referring to the drawing in detail, and wherein similar reference characters designate corresponding parts throughout the several views, the letter A designates the base section of the jack, B a cap or lift section telescopically associated with the base section A, and C an elevating or lift means arranged in the base section A and acting upon the cap section B for movement thereof in a parallel plane away from the base section A.

Referring first to the base section A, and which may be cast from any suitable material such as brass, iron, aluminum or the like, the same in the example shown is square shape in plan and embodies a flat base plate 10 provided at each marginal edge with upstanding bordering side walls 11. Each of the side walls 11 has reduced upper portions 12 which form an externally extending shoulder 13, while the lower edge of each wall has a flaring base portion 14 which projects for a short distance below the under surface of the base plate 10 as clearly illustrated in Figures 1 and 2 and which marginally extending base portions will provide a more uniform bearing and prevent wobbling of the base section upon the floor surface 15. Preferably formed or cast integral with the base plate 10 and extending in parallel relation across the upper face of the base plate, are upwardly projecting inner and outer slide ribs 16 and 17 respectively, and which ribs as will be observed in Figure 3 extend in parallel alignment with the power screw and from one end wall 11 to the directly opposite end wall.

While not entirely essential it is preferred that the outer slide ribs 17 be disposed closely adjacent the opposite side walls 11 and that

the inner ribs 16 be spaced but a short distance apart as illustrated in Figures 2 and 3. Formed on the base portion 14 of one of the side walls 11 directly below the shoulder 13, is an outwardly extending boss 18 provided with an opening or passageway 19 and which opening preferably is of elongated formation in cross section with the major cross section dimension of the opening extending vertically or at a right angle to the longitudinal axis of the side wall 11. Thus it will be seen that the base section A is of substantially box like formation and provides a pocket 20 opening at the upper side of the box like section.

Referring now to the cap or lift section B and which is also preferably formed of cast metal of a suitable nature, the same is adapted to be telescopically associated with the base section A and embodies a flat cap plate 22 being recessed at its outer face and inwardly of its marginal edges for providing a depression or socket 23, and depending from each marginal edge of the cap plate, are bordering flanges 24 of a depth substantially equal to the height of the reduced upper portions 12 of the spaced side walls 11. As will be observed in Figures 1 and 2, the inner surfaces of the depending flanges 24 slidably engage the outer surfaces of the upstanding portions 12 of the base section A. This telescopically fitting of the sections A and B serves to effectively exclude dust and dirt from entering the pocket 20. Depending from the under side of the cap plate 22 and preferably cast integral with the section B, is a series of parallel spaced apart tongues 25 being of greatest depth at their longitudinal centers and tapering therefrom in opposite directions toward the flanges 24 for forming oppositely inclined guide surfaces 26 and 27 with the guide surfaces of the tongues aligning one with the other transversely of the longitudinally arranged tongues. These tongues 25 when the sections A and B are in assembled relation, extend in substantial longitudinal alignment above each of the slide ribs provided on the upper side of the base plate 10. It may here be well to state that the overlapping of the flanges 24 and wall portions 12 also acts as guide means for preventing relative lateral shifting of the sections A and B.

As a means for retaining the sections A and B in assembled relation during shipment, it is preferred that relatively short screws 28 be threaded through opposite flanges 24 as in Figure 2 and have their inner ends movable in suitable elongated slots 29 provided in the outer faces of the base wall portions 12. These screws 28 and slots 29 will permit of relative movement of the sections A and B but prevent the sections from being separated one from the other.

In the example shown, the base portion of a table leg 30 has been shown fitting in the socket 23 provided in the outer face of the cap plate 22, but it will of course be understood that the member 30 may constitute the leg portion of any type or article of furniture.

Referring now to the elevating or lift means C, the same embodies a pair of right and left wedge or traveler members 32 and 34 respectively, and a power screw 35 engageable with the wedge members 32 and 34 for movement thereof toward and away from one another upon rotation of the screw. The wedge members 32 and 34 are of substantially identical construction and each embodies an elongated flat bottom portion 36 and an outer wall portion 37 which extends along the outer longitudinal edge of the bottom portion preferably in right angular relation therewith. Formed at the upper side of the bottom portion 36 and inner side of the outer wall portion 37, are inner and outer wedge strips 38 and 39 respectively each having correspondingly inclined upper edges 40 which slope from the upper edge of the outer wall portion 37 toward the inner edge of the bottom wall portion 36 as clearly illustrated in Figures 1 and 5. The upper edge of the outer wall portion 37 is preferably inclined to correspond with the inclination of the edges 40. These wedge strips 38 and 39 and when the wedge members are in position within the pocket 20 are disposed above the respective slide ribs 16 and 17 and have their inclined upper edges aligning with the guide surfaces 26 and 27 of the tongues 25. Thus it will be seen that the friction caused by the sliding action of the wedge members 32 and 34 is materially decreased by the edge contact between the tongues 25 and wedge strips 38 and 39. Sliding friction between the wedge members and base plate 10 is also decreased by reason of the edge contact of the ribs 16 and 17 with the under side of the wedge bottom portions 36. An arcuate shaped lug 42 depends from the longitudinal center and inner edge of the bottom wedge portions 36 and extends between the inner slide ribs 16 for reinforcement of the medial portion of the wedges and also aiding in presenting lateral or longitudinal shifting of the wedge members.

The only differing characteristics between the wedge members 32 and 34, is that the outer wall portion 37 of the wedge member 34 is provided between the wedge strips 39 with a threaded opening 44 provided with left hand threads, while the outer wall portion 37 of the wedge member 32 is provided between the wedge strips 39 with a threaded opening 46 of less diameter than that of the opening 44 and provided with right hand threads.

of a pitch corresponding with the pitch of the threads provided in the opening 44.

Referring now to the specific construction of the power screw 35, the same embodies 5 major and minor threaded shank portions 47 and 48 respectively, the threaded shank portion 48 being arranged at the terminal of the power screw and being of less diameter than that of the shank portion 47

10 which is arranged adjacent the head or operating end of the power screw. The shank portion 48 of smaller diameter is provided with right hand threads for threaded connection with the right hand threaded opening 46 while the shank portion 47 of larger

15 diameter than the shank portion 48 is provided with left hand threads for threaded engagement in the left hand threaded opening 44 of the wedge member 34. The right and left screw threads of the shank portions

20 48 and 47 respectively are of the same pitch so that upon rotation of the power screw each of the wedge members 32 and 34 will travel at an equal rate of speed. Formed at the outer end of the shank portion 47 is a thrust

25 collar 50 which bears against the inner side of the base section wall 11 at the inner end of the opening 19, and extending through the opening 19 from the collar 50 is a stem portion 51 which projects for a distance past the outer end of the boss 18 for receiving a suitable operating knob 52 preferably provided with a wrench square 53. Thus it will be seen that the boss 18 forms a bearing for

30 the outer end of the power screw 35 and by reason of the knob 52 engaging the outer end of the boss, the power screw is held against longitudinal movement when being rotated for movement of the wedge members 32 and

35 34. The opening 19 has been so formed to allow the ready insertion of the stem portion 51 through the opening from the inner side of the base section during assembly, and after which the knob 52 may be connected with the

40 projecting end of the stem. By so having the opening 44 of the wedge member 34 of greater diameter than the opening 46 of the wedge member 32, such will permit of the reduced right hand threaded shank portion 48

45 to be readily inserted through the oppositely threaded enlarged opening 44 for proper threaded connection with the right hand threaded opening of the wedge member 32.

Thus it will be seen that upon rotation of the 50 power screw that the wedge members 32 and 34 may be drawn together or moved apart by the power screw embodying right and left threads of the same pitch but of different diameters. By having the threaded portions

55 47 and 48 of the same pitch, it will be seen that the wedge members 32 and 34 will travel at equal rates of speed for movement of the traveler cap plate 22 in a perfectly parallel position toward or away from the base

60 plate 10.

While the device is primarily intended for use as a table jack, it will readily be apparent that the device may be used for various other purposes where a wedging or lifting action is to be performed.

From the foregoing description it will be apparent that an improved and novel type of jack has been provided embodying relatively few and simple parts so arranged as to reduce the over all height to a minimum and which device operates under a novel principal whereby the cap or lift section moves in a plane parallel with the supporting or base section of the device.

Changes in the shape, size and arrangement of parts may be made to the specific form of the invention herein shown and described, without departing from the spirit of the invention or the scope of the following claims.

I claim:

1. A jack of the class described comprising a hollow base section having a flat bottom wall, a cap section slidably associated with the base section and having spaced narrow tongues projecting into the hollow base section and provided with oppositely inclined guide surfaces, wedge members slidably mounted in the base section and engageable one with each of the oppositely inclined guide surfaces of said tongues, and a power screw carried by the base section and having threaded connection with each of said wedge members for imparting equal degrees of movement thereto upon rotation of the power screw.

2. A jack of the class described comprising a hollow base section, a cap section telescopically fitting over the base section and having parallel arranged tongues depending from its under side and extending into the base section for providing oppositely inclined guide surfaces, wedge members slidably mounted in the base section and each embodying wedge strips having inclined edges for aligning with and engaging the inclined surfaces of said tongues, and a power screw mounted against longitudinal movement in the base section and having threaded connection with said wedge members for imparting equal degrees of movement thereto in opposite directions upon rotation of the power screw.

3. A jack of the class described comprising a base section including a base plate and side walls, slide ribs formed in parallel relation on the upper face of the base plate, a cap section telescopically fitting over the side walls of the base section and having longitudinally arranged tongues provided with oppositely inclined guide surfaces, wedge members extending transversely of and resting upon said slide ribs and having inclined upper edges engageable with the oppositely inclined guide surfaces of said tongues, and

a power screw mounted against longitudinal movement in one side wall of the base portion in parallel alignment with said guide ribs and having threaded connection with each of said 5 wedge members for movement of the members toward and away from one another upon rotation of the power screw.

4. A jack of the class described comprising a base section embodying a flat base plate and 10 upstanding side walls, a cap section embodying a recessed top plate having depending flanges engageable with the outer surfaces of said base section walls and integral longitudinally arranged tongues at the under side 15 of the top plate provided with oppositely inclined guide surfaces, along their lower edges said tongues being of greatest height at their longitudinal centers and tapering toward the top plate at opposite flange portions thereof, 20 wedge members slidable on the flat base plate, each including a series of wedge strips having inclined upper edges for surface contact with the oppositely inclined guide surfaces of said tongues, said wedge members extending 25 transversely of said tongues, and a power screw mounted against longitudinal movement in one of the side walls of the base portion and extending in longitudinal relation with said tongues and having portions for 30 threaded connection with the wedge members for imparting equal degrees of movement thereto upon rotation of the power screw.
